ABSTRACT: In a traveling-wave tube using a periodic permanent magnet focusing system, a plurality of helix turns nearest the collector are unsupported by the dielectric support rods. This increases the tolerable electron impingement of the helix by reducing the heat transfer to the support rods and resultant contamination by out-gassing.

FIG. 3

FIG. 1C

TRAVELING WAVE TUBE HELIX SUPPORT STRUCTURE

BACKGROUND OF THE INVENTION

This invention relates to traveling-wave tubes, and more particularly, to helix support structures.

The traveling-wave tube, a well known and widely used microwave amplifier, comprises a conductive helix through which an electron beam is projected. By a process known as cumulative interaction, electric fields, associated with microwave energy propagating on the helix, couple with the electron beam such as to cause electron beam energy to be converted to microwave energy. Normally, the waves to be amplified propagate along the helix in the direction of electron beam flow, although this is not necessarily the case. Traveling-wave tubes may also be used as oscillators; that is, as microwave frequency generators.

The electron beam is normally constrained to flow within the helix by an externally applied magnetic field. As is described, for example, in C. E. Bradford, U.S. Pat. No. 3,355,622, issued Nov. 28, 1967, the weight and bulk of the external magnet system can be substantially reduced by using an array of annular permanent magnets arranged to establish a spatially alternating magnetic field along the electron beam path. The conductive helix is typically connected at opposite ends to a cylindrical input coupler and an output coupler and is supported by three dielectric support rods that may conveniently be mounted on the input and output couplers.

There is a natural tendency of the electron beam diameter, when radio frequency input power is being amplified to high amplitudes, to expand near the downstream or collector end of the helix because of the removal of the kinetic energy from the beam by the helix wave; this is especially true when the R-F input power is being amplified to a high amplitude. Beam expansion is particularly pronounced if periodic focusing is used because, when the reduced velocity electrons fall out of synchronism with the spatially alternating magnetic field, a condition is caused known as beam ripple. The expanded beam diameter may result in localized electron impingement on the downstream end of the helix with concomitant local (spot) heating to high temperatures. With excess electron impingement, the support rods will be heated to such an extent that first, their dielectric constant changes significantly; and secondly, gases are driven from the rods. The change of dielectric constant changes the helix wave velocity to throw it out of synchronism with the electron beam, thereby reducing device efficiency, while the gases driven from the rods create ion noise and eventually contaminate the cathode.

One way of avoiding the problem is simply to make the helix diameter sufficiently large. This, however, reduces interaction efficiency and attainable amplification. One could also make the support rods of a thermally conductive material such as beryllia, but this approach is expensive for a variety of reasons, such as the brittleness of the material.

SUMMARY OF THE INVENTION

In accordance with the invention, the problems associated with excessive support rod heating are substantially reduced or eliminated by separating the helix turns nearest the collector from the support rods. Normally, each helix turn is bonded, as by glazing, to all of the support rods, and this is true of about 95 percent of the turns of the helix of my tube; the 5 percent at the downstream end of the helix are suspended between the bonded helix structure and the output coupler.

The separation is best achieved by reducing the cross section of the support rods in the region of the separated helix turns. Because the tube envelope is evacuated, the separation is a vacuum gap and the support rods are well insulated thermally from the uncontacted helix turns. Hence, even though the downstream end of the helix may be impinged by electrons, the resultant heat is not transferred directly to the support rods, a greater portion of heat is dissipated by radiation,

and intense local heating of the support rods is substantially eliminated. For the reasons given before, this increases the efficiency and lifetime of the entire traveling wave tube.

These and other objects, features, and advantages of the invention will be better understood from a consideration of the following detailed description taken in conjunction with the accompanying drawing.

DRAWING DESCRIPTION

FIGS. 1A and 1B together are a sectional view of a traveling-wave tube in accordance with an illustrative embodiment of the invention;

FIG. 1C illustrates how FIGS. 1A and 1B are intended to fit together;

FIG. 2 is an enlarged view of part of the traveling-wave tube of FIG. 1; and

FIG. 3 is a view taken along lines 3-3 of FIG. 2.

DETAILED DESCRIPTION

Referring now to FIG. 1, there is shown a traveling-wave tube, the purpose of which is to amplify electromagnetic waves transmitted by an input waveguide 11, an input coupling member 12, a helix 13, an output coupling member 14, and an output waveguide 15. An electron beam is formed and projected along the helix axis by an electron gun comprising a cathode 16, beam forming electrode 17, and accelerating anode 18. The beam is maintained within a vacuum by an evacuated envelope 20 and is collected by a collector electrode 21. An array of annular permanent magnets 22 surrounding the envelope focuses the beam and constrains it to flow along the central axis to the collector in accordance with the principles of periodic focusing. An array of pole pieces 23 maintains the desired spatial periodicity of the magnetic field in accordance with the principles described in C. E. Bradford U.S. Pat. No. 3,355,622, issued Nov. 28, 1967, and assigned to Bell Telephone Laboratories, Incorporated.

In accordance with well-known principles of traveling-wave tube operation, the electron beam velocity and the helix pitch are appropriately interrelated so that the wave on the helix travels in approximate synchronism with the beam. Axial fields associated with the wave modulate component electrons of the beam to form space-charge waves which are coupled with the helix as they travel toward the collector. The coupled waves abstract drift velocity energy from the beam and convert it to microwave energy such that the wave appearing at the output waveguide is an amplified form of that introduced by the input waveguide.

As is seen more clearly in FIGS. 2 and 3, the helix 13 is supported by three axially extending dielectric rods 25, each bonded to an extending between the input and output couplers 12 and 14. As was mentioned before, there is a tendency for the rods to become excessively heated due to electron impingement on the downstream end of the helix. This effect is especially pronounced in a periodically focused electron beam because the magnetic field spatial alternations create a condition known as beam ripples, manifested by predictable periodic locations of expanded beam diameter. As the beam velocity is reduced, due to high R-F fields, the ripple is increased, and unless the helix diameter is unduly large, a maximum-diameter region of the beam impinges the helix near the downstream end. With a normally constructed helix assembly, the resultant heat would be transmitted directly to the support rods and, for the reasons given before, device efficiency and lifetime would be limited.

In accordance with the invention, tube efficiency and lifetime are increased by separating the last 10 turns of the helix from the support rods. This is preferably done by cutting away a portion of the support rods and the final 10 turns of the helix. The gap constitutes a vacuum insulation between the helix and the support rods and prevents heat from being directly transferred between those helix turns and the support rods. The majority of the helix turns each contact the support

rods and are each glazed to all of the support rods as is customary in the art.

The tube of FIG. 1, in which the invention has been used, has the following characteristics:

Ration of beam diameter to

helix diameter	(b) (a)	.5
Average helix diameter	inch	.1023
Frequency of operation	gigahertz	5.925-6.425
Beam current	amps	.059
Helix length	inches	8.04
Helix turns per inch		24.09
Helix synchronous voltage	volts	39.50
Peak focusing field	gauss	1070
Magnetic field period	inch	.606
Cathode diameter	do	.246
Collector voltage	volts	1800
Anode voltage	do	4350
Heater voltage	do	6.8

A solenoid coil 28 surrounding the electron gun provides a magnetic field for matching to the field provided by magnets 22 and suppresses buildup of beam noise. A shielding member 29 surrounding the gun prevents magnetic fringing fields from extending into the electron gun. A cylindrical conductive member 30 defines with the shielding member 29 and coupling member 32, a radial waveguide 31 that acts as a choke at the operating frequency and thereby forces the input waves to propagate along the helix as desired. An annular aluminum casting provides structural stability to the assembly. With these parameters, it can be shown that the tube gives relatively high efficiency interaction while avoiding the problems that would normally arise from excessive heating of the support rods. The tube parameters, particularly the ratio of beam diameter to helix diameter, are designed such that significant beam impingement occurs only on those helix turns separated from the support rods. As used herein, the term "helix" denotes any twisted wire slow wave structure, and is not intended to be used in the mathematical or geometric sense.

The specific embodiment shown described is intended to be only illustrative of the principles involved. Various other embodiments and modifications may be made by those skilled in the art without departing from the spirit and scope of the invention.

I claim:

1. In a traveling-wave tube of the type comprising means for forming and projecting a beam of electrons, means for

propagating high frequency energy in interacting relation with the beam comprising an elongated conductive helix extending coaxially with the beam and arranged such that the beam enters an upstream end of the helix and exits from a downstream

5 end, and means for supporting the helix comprising a plurality of dielectric support rods each parallel to the helix axis and contacting the helix, the improvement wherein: a plurality of helix turns immediately adjacent the downstream end of the helix are out of contact with the support rods and separated from the support rods by a vacuum gap, thereby inhibiting heat transfer from said plurality of turns to the support rods.

10 2. The improvement of claim 1 wherein: approximately 95 percent of the helix turns contact the support rods; and

15 3. In a traveling-wave tube of the type comprising means for forming and projecting a beam of electrons from a cathode to a collector, means for focusing the electron beam, and means

20 for propagating high frequency energy in interacting relation with the beam comprising a conductive helix extending from an input coupler member near the cathode to an output coupler member near the collector, the improvement comprising: means for supporting the helix comprising a plurality of

25 dielectric support rods, each mounted at one end on the input coupler member and at the opposite end on the output coupler member; the major part of each support rod being bonded to successive turns of the helix;

30 a minor part of each support rod being located immediately adjacent the output coupler member and having a cross-sectional area that is smaller than that of the major part; and

35 a plurality of helix turns being coextensive with the minor part of the support rods and being unconnected to the support rods, thereby inhibiting heat transfer to the support rods.

4. The improvement of claim 3 wherein: said focusing means comprises a periodic permanent magnet focusing system.

40 5. The improvement of claim 4 wherein: the periodic permanent magnet focusing results in electron beam ripple, a ripple amplitude during operation growing with distance in the direction of the collector; and the ratio of the average beam diameter to the helix diameter being such that a maximum amplitude portion of the beam impinges on part of said plurality of helix turns coextensive with the minor parts of the support rods.
